UNITED STATES PATENT OFFICE

CARLIN A. WALSH, OF CAMBRIDGE, MASSACHUSETTS

ARTIFICIAL TOOTH

Application filed March 13, 1929. Serial No. 346,732.

My present invention relates to artificial teeth, and includes novel features of construction which enable teeth constructed according to said invention to be used either as 5 pivot teeth or in association with bridgework.

An important object of the present invention consists in the provision of an artificial tooth formed with a metallic backing and reinforcing plate, and in providing said backing plate with a substantially vertically extending pin which preferably projects above the gingival edge for attachment to a root, when used as a pivot tooth.

Another object of the invention resides in 15 constructing said metallic backing plate with a laterally projecting lip or lips, integral with said backing plate, to provide a strong incisal edge or surface.

A further object of the invention resides in 20 providing the main body portion of the tooth, which is preferably formed of porcelain or other ceramic material, with a plurality of ledges or shoulders, against which portions of the backing plate will bear, to provide reinforcements for said backing plate to prevent vertical movement thereof during biting 25 or chewing.

Another object of the invention consists in inclining one of said ledges in such a manner as to prevent any rocking of the backing plate.

A still further feature of the invention resides in providing the porcelain body of the tooth with a substantially vertical recess, adjacent to one of said shoulders, through which the aforesaid pin will pass, said pin preferably extending substantially above the gingival edge of the tooth and by means of which the tooth may be fixed as a pivot tooth 40 to a natural root.

In the event that it is desired to affix my novel tooth to a bridge, instead of to a natural root, the pin may be sheared off at the top of the porcelain body and cemented or otherwise secured to the bridge.

My present tooth is strong, efficient, simple and economical to manufacture, easy to apply or install, and since I believe the same is novel, I have therefore claimed said tooth broadly in the present application.

The above and other features of the invention, details of construction, combinations of parts, and advantages, will be hereinafter more fully pointed out, described and claimed.

Referring to the drawings, illustrating a preferred embodiment of the invention,

Fig. 1 is a front elevation of an incisor embodying my invention;

Fig. 2 is a side elevation of said incisor; 60

Fig. 3 is a rear elevation of said incisor;

Fig. 4 is a sectional side elevation of said incisor;

Fig. 5 is a side elevation of a molar embodying my invention;

Fig. 6 is a front elevation of said molar;

Fig. 7 is a front elevation of a bicuspid with a slightly modified form of shoulder construction; and

Fig. 8 is a side elevation of the bicuspid 70 illustrated in Fig. 7.

Referring now to the drawings for a particular description of the invention, its construction and assembly, 1 designates a body portion of porcelain or other ceramic material having a labial face 2 and a face 3, forming a portion only of the lingual face of the tooth. The entire gingival, or gum-contacting edge 4 is formed directly in the porcelain body portion 1, thus eliminating any contact of metal at the gingival margin with the gum of the patient.

The body portion 1 is provided with a downwardly inclined shoulder or ledge 5, and with a bottom edge 6, which is preferably substantially straight, although it may also be inclined somewhat if desired. Extending substantially vertically through the upper portion of the body 1 is an aperture 7, the bottom of said aperture opening onto the shoulder 5, and the front wall of said aperture being preferably a continuation of the straight rear edge 8 of the body 1.

I next provide a backing plate 9, preferably of gold, although other metals may be utilized if desired, as will be understood and appreciated. This plate has a straight contacting face 10 adapted to contact with the straight rear face 8 of the body 1, and to be cemented thereto. The plate 9 also has a 100

face 11, which with the face 3 of the body 1, forms the complete lingual face of the tooth. The backing plate 9 extends below the body 1 a sufficient distance to form the 5 incisal or biting edge 12, and the lower portion of the plate has a ledge or shoulder 13 adapted to abut against the ledge or shoulder 6 of the body 1. This construction compels 10 all biting to come on the metallic incisal edge 12, and prevents any chipping or splitting of the labial face of the body 1.

The plate 9 is also constructed or formed with an inclined upper edge 14, adapted to abut against the shoulder 5 of the body 1, 15 the upper portion of the plate 9 being thus securely housed in the recess formed by the shoulder 5, as clearly illustrated in Figs. 2 and 4, which will entirely eliminate any rocking of the plate. Vertically extending from 20 the top of the plate 9 is a post or pin 15, this pin passing through the aperture 7 in the body 1 and here illustrated as extending above the gingival edge 4 for a substantial 25 distance. The tooth illustrated in Figs. 1 to 4, with the pin or post 15 as shown, is adapted for a pivot tooth, the pin 15 being embedded and anchored in a natural root (not shown). If, however, it should be desired to utilize this tooth in a bridge, the pin 15 would either 30 be sheared off flush with the top of the body 1, or would be initially constructed of such a length as not to extend above the top of said body 1.

It will be readily understood and appreciated by those skilled in this art that my novel tooth is strong, rugged and efficient, is simple to manufacture, assemble and install, either as a pivot tooth or as a component part of a bridge, and is possessed of numerous advantages and benefits to the wearer thereof.

While Figs. 1 to 4 inclusive illustrate my invention as applied to an incisor, my invention is nevertheless equally applicable to molars or bicuspids, and in Figs. 5 to 8 inclusive I have illustrated the invention as applied to these types of teeth.

In Figs. 5 and 6 illustrating a molar, 16 designates the main body portion of the tooth, of porcelain or other ceramic material having a labial face 17 and having a posterior face 18, together with a gingival edge 19. At the lower portion of the body 16 is provided an abutment 20, here illustrated as straight, while the posterior portion of the body is also 55 provided with an abutment 21, also illustrated as straight.

It will be appreciated, however, that inclined shoulders or abutments may be utilized if desired. Extending vertically through the 60 body portion 16, from the bottom of the posterior portion of the tooth, are apertures 22, the front walls of these apertures being continuations of the vertical wall 28. A metallic backing plate or member 23 has incisal 65 or grinding surfaces 24 and a shoulder 25

adapted to abut against the shoulder 20. The member 23 has a level top surface 26 adapted to abut against the shoulder 21 and also has a vertical wall 27 adapted to engage the vertical wall 28 of the porcelain portion 16. All 70 of these contacting or abutting surfaces are preferably cemented or otherwise united. Extending upwardly from the top of the member 23 are pins or posts 29, the front walls of which are continuations of the wall 27, said 75 pins passing through the apertures 22 and above the gingival edge 19 to act as pivot pins, although they may be sheared off at the top of the porcelain body portion if desired for attachment to a bridge. While I have illustrated two pins 29 for use in a molar, it will be appreciated that I may utilize but a single pin if desired, the double post or pin structure, however, resulting in a much stronger and more rugged tooth. The posterior face 30 of the member 23 cooperates with the posterior face 18 of the porcelain portion 16 to form the lingual face of the completed tooth. In this tooth, as in the tooth illustrated in Figs. 1 to 4 inclusive, 80 there will be no metallic portions to come in contact with the gums of the wearer, the porcelain gingival edge being the only part which would have an contact with the gums. The shoulders 20 and 21 will effectually prevent 85 an upward movement of the metallic member 23, while the shoulder 25 will eliminate splitting or chipping of the porcelain on the 90 labial surface.

Figs. 7 and 8 illustrate the invention applied to a bicuspid, the porcelain body portion 31 having a labial face 32 and a posterior face 33, and a gingival edge 34. The bottom of the porcelain body 31, at the front thereof, terminates in an inclined surface 35, while an inclined surface or abutment 36 is provided at the bottom of the rear or posterior portion. An aperture 37 is provided through the body 31, extending upwardly from the surface 36, the front wall of this aperture being a continuation of the straight surface 43. A metallic member 38 has grinding surfaces 39 and has an inclined shoulder 40 to engage the surface 35. Said member 38 also has an inclined surface 41 to engage the surface or shoulder 36, the straight surface 42 of this member 38 contacting with the wall 43 of the porcelain body 31. All of these aforementioned contacting surfaces and walls are adapted to be cemented or otherwise united. The posterior wall or face 44 of the member 38 cooperates with the posterior surface 33 of the porcelain body 31 to form the lingual face of the completed tooth.

Projecting upwardly from the surface 41 is a pin or post 45, passing through the aperture 37 and to serve the same function as the pins 15 and 29 heretofore described.

In all the forms of teeth illustrated and de-

scribed herein the outer surfaces thereof will be smooth and even, there being no projecting members to annoy the wearer, and there being no objectionable recesses or crevices to 5 retain food. All these forms of teeth present a neat and attractive appearance, and are strong and durable.

The construction of each form of tooth illustrated herein provides an extremely strong 10 retention for the backing plate or member of metal, in addition to the cementing feature. The further feature of the pin or post in each instance passing through the porcelain body portion further increases the strength and 15 immovability of the metallic member.

All of these advantages will be instantly 20 apparent to those skilled in the art, and the benefits derived from the use of my novel teeth will be appreciated by the wearers thereof.

While I have necessarily described my present invention somewhat in detail, it will be appreciated that I may vary the size, 25 shape and arrangement of parts within reasonably wide limits without departing from the spirit of the invention.

My invention is further described and defined in the form of claims as follows:

1. An artificial tooth comprising a body 30 portion of ceramic material and a metallic backing for said body portion, said body portion and said backing cooperating with one another to form an artificial tooth simulating a natural tooth in size and shape, said backing having a front surface abutting a rear surface of the body portion and said body portion having an apertured inwardly directed extension providing a shoulder extending the entire width of the tooth and to 35 the rear face thereof at the gingival end of the tooth against which the adjacent end of the backing abuts, said aperture extending entirely through said extension, said backing having a pin extending through the aperture 40 in said inwardly directed gingival extension.

2. An artificial tooth comprising a body portion of ceramic material and a metallic backing for said body portion, said body portion and said backing cooperating with one 50 another to form an artificial tooth simulating a natural tooth in size and shape, said backing having a front surface abutting a rear surface of the body portion and said body portion having an inwardly extending 55 shoulder adjacent to the gingival end of the tooth against which the adjacent end of the backing abuts, said shoulder and the adjacent end of the backing being inclined inwardly towards the gingival end of the tooth, 60 the said body portion having a vertical opening through said shoulder, and a pin on said backing extending through said opening.

3. An artificial pivot tooth comprising a 65 body portion of ceramic material and a me-

tallic backing for said body portion, said body portion and said backing cooperating with one another to form an artificial tooth simulating a natural tooth in size and shape, said backing having a front surface abutting a rear surface of the body portion and said body portion having an apertured inwardly directed extension providing a shoulder extending the entire width of the tooth and to the rear face thereof at the gingival end of the tooth against which the adjacent end of the backing abuts, the front wall of said aperture being a continuation of the rear surface of the body portion, said shoulder and the adjacent end of the backing being inclined inwardly towards the gingival end of the tooth, and a pin on said backing extending through the aperture in said inwardly directed extension beyond the gingival end of the tooth to constitute means for fastening the tooth in the mouth.

In testimony whereof, I have signed my name to this specification.

CARLIN A. WALSH.
